UNITED STATES PATENT OFFICE

GEORGE SAKIER, OF NEW YORK, N. Y., ASSIGNOR TO STANDARD SANITARY MANUFACTURING COMPANY, OF PITTSBURGH, PENNSYLVANIA, A CORPORATION OF NEW JERSEY

DESIGN FOR A BATHTUB

Application filed July 19, 1930. Serial No. 36,404. Term of patent 14 years.

To all whom it may concern:

Be it known that I, GEORGE SAKIER, a citizen of the United States, residing at the city of New York, in the borough of Manhattan, county and State of New York, have invented a new, original, and ornamental Design for a Bath Tub, of which the following is a specification, reference being had to the accompanying drawings, forming a part thereof.

In the drawings—

Figure 1 is a top view showing a bath tub embodying my said design;

Fig. 2 is a front view, and

Fig. 3 is an end elevation.

I claim:

The ornamental design for a bath tub, as shown.

GEORGE SAKIER.
